TOILET FLUSH TANK TRIP LEVER CONSTRUCTION

Jesse C. Owens, Los Angeles, Calif.

Application January 24, 1951, Serial No. 207,620

3 Claims. (Cl. 4-67)

1

This invention relates to water closet flush tank outlet valve operating devices.

An object of my present invention is to provide a valve operating device of the type indicated which is adapted for quantity production and which is of exceptionally economical construction, and which, therefore, is adapted for sale at a highly competitive cost, without, however, any sacrifice in strength, durability, efficiency of operation, ease of installation, or appearance of the parts of the apparatus which are exposed to view after installation.

A more detailed object of the invention is to provide a valve operating mechanism of the general character described in which the lever portion whereby the normally operating handle on the outside of the tank is operably connected to the valve lifting bracket within the tank is a suitable length of strip brass of standard, stock size, bent at the proper places to define a lever of the desired proportion, thus dispensing with the necessity of fabricating this portion of the trip mechanism from cast metal and performing various machining operations thereon as is required by more conventional forms of toilet tank valve trip devices now in common use.

A further object in this connection is to provide means for journaling the flat strip within the tubular bore of the bushing which extends through the wall of the flushing tanks, and thereby making for an efficient rocking support of the lever as though the pivot portion were of a cylindrical form in accordance with common practice.

A further detailed object is to provide improved means for attaching the valve operating bracket to the lever in such a manner that binding of the parts and consequent interference with proper functioning of the valve are effectively prevented.

The invention possesses other objects and features of advantage, some of which, with the foregoing, will be set forth in the following description of the preferred form of my invention, which is illustrated in the drawings accompanying and forming part of the specification. It is to be understood that I do not limit myself to the showing made by the said drawings and description, as I may adopt variations of the preferred form within the scope of my invention as set forth in the claims.

Referring to the drawings, Figure 1 is a view taken in horizontal section through a portion of the front wall of a water closet flush tank and showing, in top plan, a valve operating device.

2

operably installed thereupon, portions of the showing of the operating device being broken away and shown in section the better to reveal constructional details thereof.

Figure 2 is an enlarged view in transverse, vertical section taken upon the line 2-2 of Figure 1, with the direction of view as indicated.

Figure 3 is an elevational view of the inner end of the mounting bushing which may be considered a vertical, sectional view taken upon the line 3-3 of Figure 2, with the direction of view as indicated, a portion of the figure being broken away and shown in section.

Figure 4 is a vertical, sectional view taken upon the line 4-4 of Figure 2, with the direction of view as indicated, to show the manner of mounting the handle upon the outer portion of the trip lever.

Figure 5 is a detail view showing a slightly modified form of construction for releasably retaining the lever in suitable operative position with respect to its mounting bushing.

Figures 1 and 2 illustrate the manner of mounting the flush tank valve operating mechanism of the present invention upon the front wall 6 of a conventional water closet flush tank. A bushing 7 comprising a tubular body portion 8 and an enlarged head 9 on the outer end thereof is disposed with its body portion 8 extending through a suitable opening 11 in the front wall 6 of the flush tank so as to dispose the under surface of the head 9 in contact with the outer surface of the wall 6 against which it is tightened by means of a nut 12 threaded upon the inner end of the body portion 8, exterior threads 13 being provided upon the body portion 8 for that purpose. Preferably, both the bushing 7 and the nut 12 are composed of suitable non-corrodible material such as the relatively inexpensive cast metal commonly employed for such purposes. It is evident, therefore, that the bushing 7 is firmly attached to the wall 6, rigid therewith so that it provides an adequate, stationary support for the operating lever 16 of the trip lever which constitutes an important portion of my present invention.

In order to facilitate holding the bushing 7 against rotation while the nut 12 is being tightened thereon, I prefer to provide a non-circular portion 17 on the tubular body portion 8 of the bushing immediately adjacent the head 9, which fits the hole 11 in the wall 6 of the tank loosely enough to permit its being inserted readily thereinto and yet sufficiently tightly to prevent the

bushing 7 from rotating about its own axis with respect to the wall 6.

In more conventionally constructed flush tank valve trip lever mechanisms, it has been customary to fashion that portion of the trip lever which extends through the mounting bushing to cylindrical form, fitting the bore of the associated bushing fairly accurately so as to provide a journal mounting for the lever. In the present invention, however, I depart from this relatively expensive procedure by forming the entire trip lever 16 of a single piece of flat strip stock 21, preferably of brass. In so forming the lever 16, either before or after the strip 21 has been cut to suitable length, it is bent at right angles, as indicated at 22, and again in the opposite direction, as indicated at 23, so as to define a lever composed of three principal portions, to wit, a portion 24 disposed outside the tank and adapted to extend parallel to and spaced slightly from the outer face of the wall 6 of the tank, a portion 26 disposed inside the tank 6 and adapted to extend parallel to and spaced from the inner face of the wall 6, and an intermediate portion 27 interconnecting the two portions 24 and 26. The intermediate portion 27 extends through the bore 28 of the body portion 8 of the bushing 7 and is disposed with its transverse dimensions extending substantially diametrically of the bore of the bushing and in a vertical plane. Being so disposed, the outer portion 24 of the lever extends horizontally to one side of the intermediate portion 27 while the inner portion 26 of the lever also extends horizontally, but to the other side of the intermediate portion, as clearly shown in Figure 1. Either or both of the bends 22, 23 should be formed in the strip 21 after the strip has been disposed with that portion thereof which is to constitute the intermediate portion 27 extending through the bushing, inasmuch as the desirable arrangement is that in which the intermediate portion 27 of the strip is only slightly longer than the bushing 7, with the result that the laterally extending portions 24 and 26 cooperate with the associated ends of the bushing to secure the strip against accident removal from the bushing and without any binding that might operate to restrict free rocking movement of the lever about the axis of the bushing.

Preferably at least one disc 31 is disposed within the bore 28 of the bushing, this disc 31 having a slot 32 which extends substantially diametrically with respect to the disc and within which the intermediate portion 27 of the lever 16 fits fairly tightly. The circular periphery 33 of the disc 31, however, is fitted to the bore 28 of the bushing 7 for freedom of rotation therein, with the result that the disc can move with the lever 16 and with respect to the bushing when the lever is moved in rocking movement as in performing the operation of lifting the outlet valve of the flush tank. The disc 31, therefore, serves as a bearing support for the intermediate portion 27 of the lever 16, holding the intermediate portion in axial alignment with the body portion 8 of the bushing and therefore assuring freedom of the desired rocking movement of the lever 16.

I prefer to provide means for limiting the degree of rocking movement of which the lever can partake to a few degrees of rocking movement, approximately 5° or 10° of such rocking movement being all that is necessary to attain complete operation of lifting the valve from its seat.

A preferred form of such means for limiting extent of rocking movement is in the nature of

a pin 36 threaded through the wall of the body portion 8 of the bushing and extending at least radially of the bore thereof far enough to pass through a hole 37 in the intermediate portion 27 of the lever 16, this hole 37 being slightly larger than the pin 36 so that the strip can move through the desired degree of rocking movement before the edges of the hole 37 engage the stationary pin 36.

10 A preferably ornamental handle 41 is rigidly and preferably permanently attached to the outer portion 24 of the lever 16. This handle comprises a hub portion 42 and an arm portion 43 extending radially therefrom. Both the hub and arm portions 42 and 43 are of hollow construction, open at the back, permitting the handle to be inserted into position upon the outer portion 24 of the lever 16 with the hub portion 42 extending over the head 9 of the bushing 7 until the inner peripheral edge 44 of the hub 42 is closely adjacent the outer face of the wall 6 of the tank. Preferably the distance that the handle can be inserted over the head 9 and toward the front wall 6 is limited by a plurality of bosses or fins 46 on the inner surface of the head 42. Within the hollow interior of the arm 43 of the handle 41 preferably a pair of columns or bosses 47 are provided, each having a flat surface or land 48 adjacent its outer end and the lands 49 of the two bosses 47 being in planar alignment with each other. Upstanding from each of the lands 48 is a pin portion 49 adapted to fit fairly tightly within and to extend through a suitably positioned hole 51 in the outer portion 24 of the lever 16 and to be riveted over any contact with the inner surface of the associated portion of the flat strip 24, as indicated at 52, so as to attach the handle 41 rigidly and permanently to the outer portion 24 of the lever 16.

20 25 30 35 40 45 50 55 60 65 70 75 Thus it may be seen that the arm 43 of the handle 41 encloses and conceals most of the outer portion 24 of the lever 16 and the hub 42 encloses and conceals the remaining portion of the outer portion 24 and the head 9 of the mounting bushing 7.

The inner portion 26 of the lever 16 is preferably offset to a position more distant from the inner surface of the wall 6 of the tank than the inner end of the bushing 7, a pair of suitably spaced and oppositely directed bends 56 and 57 being provided for this purpose, thus providing for ample clearance between the portion 26 of the lever and the tank's wall 6, and still leaving the short portion of the lever between the bends 23 and 56 extending radially and sufficiently close to the inner end of the bushing 7 to serve as an abutment adapted to bear thereagainst and thus limit outward axial movement of the intermediate portion 27 of the lever with respect to the bushing 7.

65 70 75 This inner portion 26 of the lever 16 comprises a body portion 61 and an end portion 62 parallel to and spaced slightly from the body portion 61 and connected thereto by a reverse bend 63 at the outer end of the body portion. A series of holes 64, 65 are formed in the end portion 62 and with each hole 64, 65 a similar hole 66, 67 is aligned in the body portion 61, thus presenting a series of aligned pairs of holes through any one portion of which the upper end 68 of a bracket 69 can be engaged, this bracket 69 constituting the means whereby the lever 16 is operatively connected to the outlet valve (not shown) for controlling escape of water from the tank to the toilet fixture (not shown). It is common prac-

tice to attach such a bracket ν to the lever by which the valve is elevated by simply passing the piece of wire of which the bracket is conventionally constructed through a suitable hole in the lever and then bending the wire downwards at both sides of the lever. However, if the lever is relatively thin, the two bends in the wire and at opposite ends of the hole will be so close together that there will be substantially no straight portion of the wire between the two bends and binding of the wire within the hole will be apt to develop to such an extent that efficient operation of the valve is interfered with. However, by providing the two spaced portions of the flat strip, through both of which the two aligned holes 64 and 66 or 65 and 67, as the case might be, extends, when the wire is bent downwards at the outer end of say the hole 64 and at the outer end of its associated hole 66, the two bends thus made in the wire will be so far apart that a very substantial length of straight wire will remain at the top 68 of the bracket, thus assuring freedom of rotation of the portion 63 within the holes 64 and 66.

I claim:

1. In a toilet flush tank trip lever mechanism, a mounting bushing comprising a tubular shank and means for securing said bushing in position extending through a wall of a tank comprising a head rigid with the outer end of said bushing and a clamping nut threaded on the inner end of said bushing, a flat metal strip comprising an outer portion extending laterally from the outer end of said bushing, an inner portion extending laterally from the inner end of said bushing, an intermediate portion interconnecting said inner and outer portions and extending through said bushing and rotatable therein about the axis thereof, and a portion extending radially from the inner end of said intermediate portion closely adjacent the inner end of said bushing to provide an abutment adapted to engage the inner end of said bushing and thereby limit outward axial movement of said intermediate portion with respect to said bushing means for connecting a flushing valve to said inner portion of said strip, a handle comprising a hub and an arm extending radially therefrom said hub and said arm both being of hollow, open back construction and enclosing and concealing, respectively, said bushing's head and said outer portion of said strip, and means for affixing said handle to said strip comprising a plurality of bosses projecting from the inner surface of said handle's arm and hav-

ing lands in planar alignment with each other, and a pin projecting from each of said lands through and fitting within a hole in said outer portion of said strip, and an enlarged head on the outer end of each of said pins.

2. In a toilet flush tank trip lever mechanism, a mounting bushing, means for securing said bushing in position extending through a wall of a tank, a flat metal strip comprising an outer portion extending laterally from the outer end of said bushing, an inner portion extending laterally from the inner end of said bushing, and an intermediate portion interconnecting said inner and outer portions and extending through said bushing and rotatable therein about the axis thereof, a pin rigid with said bushing and extending radially of the bore thereof through a hole in said strip of slightly greater diameter than said pin to limit rotary motion of said intermediate portion of said strip with respect to said bushing, and means for connecting a flushing valve to said inner portion of said strip.
3. In a toilet flush tank trip lever mechanism, a mounting bushing, means for securing said bushing in position extending through a wall of a tank, a flat metal strip comprising an outer portion extending laterally from the outer end of said bushing, an inner portion extending laterally from the inner end of said bushing, and an intermediate portion interconnecting said inner and outer portions and extending through said bushing and rotatable therein about the axis thereof, said inner portion of said strip comprising a body portion and an end portion parallel to and spaced therefrom and connected thereto by a return bend at the outer end of said body portion, said end portion having a series of holes therethrough, each of said holes being aligned with a similar hole in said body portion to provide a bearing substantially greater in length than the thickness of said strip.
